CODE FINDING KEY

Reuben Simon, Detroit, Mich.

Application July 10, 1934, Serial No. 734,452

1 Claim. (Cl. 70—9)

It has been the practice to provide a complete series of code finding keys for the locks of each manufacturer, the number of such keys necessarily equalling the number of combinations of notches and notch depths employed by such manufacturer. Thus, for example, if a manufacturer provides in his series, keys having five notches varying in depths from one to five units then the possible number of combinations equals five raised to the fifth power. In such instances a key maker would require that number of code finding keys in order to determine the code number of the key for a particular lock, the uses of such code finding keys being entirely familiar to those skilled.

15 The object of the present invention is to provide an improved code finding key which will make it possible to reduce the number of code finding keys necessary to determine the code number of a key for a particular lock. Taking the example 20 set forth above, by way of illustration, where present practice requires a total number of code finding keys equal to the number of notches raised to that power equal to the number of notch depths employed, the present invention makes it possible 25 to reduce that number of code finding keys to a number equal to the number of notches, minus one, raised to that power equal to the number of different notch depths. Stated numerically, while present practice would require 3125 different 30 code finding keys where five notches are employed with five different depths, the present invention makes it possible for 1024 different code finding keys to serve the purpose for such a series of locks. Such a result follows in accordance with 35 the invention regardless of the number of notches and number of different notch depths.

In accordance with the invention a code finding key is provided which has a number of notches for coaction with the tumblers equal to the number of tumblers, minus one, and a cam surface to 40 actuate the remaining tumbler. The notches thus provided in the improved code finding key are of such width at their bases (considered longitudinally of the shank of the key) as to permit free 45 longitudinal movement of the key without moving the respective tumblers, for a distance sufficient to permit the said cam to move the said remaining tumbler throughout its effective locking range. Thus, having the correct code finding 50 key for all of the tumblers save one the remaining tumbler, by proper manipulation of the key, can be cammed out of locking position and the cylinder of the lock (if it be a cylinder lock) 55 revolved freely. With this determination the required key can be readily formed from a blank

since the code number is known for all of the notches save one and the depth of that notch can be determined readily by trial.

The invention will be more fully described in connection with the embodiment illustrated in the 5 accompanying drawing, wherein:

Figure 1 is a view in section showing somewhat conventionally a cylinder lock and its tumblers, mounted within a barrel, and in side elevation, a code finding key embodying the improvements, in 10 its relation to the tumblers.

Figure 2 is a view in side elevation of a code finding key embodying the invention but of slightly modified form.

The improvements have been illustrated and 15 will be described with reference to cylinder locks. A code finding key is used, as the name implies, to determine the code numbers of a key to fit a particular lock. According to the make of lock it is known, of course, how many tumblers are 20 provided so that the problem in fitting a key to the lock is to determine the notch depths for the respective tumblers. There has been illustrated in Figure 1, in conventional form, a barrel *a* of a lock having mounted revolubly therein a cylinder 25 *b* in which are carried five tumblers *c*, *c'*, *c²*, *c³* and *c⁴*, these tumblers being movable by the proper key into such relation to the barrel as to permit the cylinder to revolve. In accordance with present day practice a key maker is provided 30 with a series of code finding keys which he must use by trial and error until he locates the right one to free the tumblers from the barrel. In the case illustrated, for example, there are five tumblers and so the desired key would have five 35 notches. It may be assumed that these several notches have five different depths. Accordingly, a complete series of code finding keys to ascertain the correct code number would equal in number five raised to the fifth power. Obviously, the 40 number of such code finding keys required is an important practical consideration both as regards initial expense and facility in determining the correct combination. In accordance with the present invention, under the example given, the 45 number of code finding keys required would be reduced to four raised to the fifth power.

Referring now to Figure 1 it will be seen that the improved code finding key *d* has four notches *d'*, *d²*, *d³*, *d⁴*, the number of notches being one 50 less than the number of tumblers. Each of these notches at its base is of greater width than the thickness or diameter of the tumblers *c*, *c'*, *c²*, *c³*, respectively, with which they coact. This additional width permits the key *d* to be moved freely 55

longitudinally within the limits of the notches without actuation of the several tumblers seated therein. Having selected a code finding key with the proper notches d' , d^2 , d^3 , d^4 , for coaction with the respective tumblers c , c' , c^2 , c^3 , the remaining tumbler c^4 must be retracted from the barrel to permit the cylinder to turn. This is accomplished by forming at the end of the key a cam surface d^5 which coacts with the tumbler c^4 upon longitudinal movement of the key d . By proper feel the cam d^5 is caused to move the tumbler c^4 into proper relation to the barrel to permit the cylinder to revolve. Having accomplished this the operator knows that the particular code finding key employed has the first four notches of proper depth. He thereupon files a blank with four notches of the depth equal to the respective notches d' , d^2 , d^3 , d^4 . The depth of the fifth notch he thereupon determines by trial and error filing it to the successive possible notch depths until he finds the tumbler c^4 in proper relation to the barrel to permit the cylinder to revolve.

In Figure 2 is shown a slight modification of an improved code finding key D. In this embodiment the notches of predetermined depth are illustrated at D^2 , D^3 , D^4 and D^5 , the last notch D^5 being in the position of the fifth notch of the key at the end of the shank. These several notches are adapted to coact in normal manner with the respective tumblers illustrated in Figure 1 at c' , c^2 , c^3 , c^4 . When using the code key illustrated in Figure 2 the fifth tumbler c is engaged for actuation by a cam surface formed in a narrow notch D' , this notch being of maximum depth for the particular series of keys, this maximum depth in the example assumed being five units. It will be noted that in this embodiment the key notches D^2 , D^3 , D^4 , D^5 , are of greater width than the tumblers, as explained heretofore, so that the key D may be moved longitudinally to cause the cam surface of the notch D' to coact with the remaining tumbler c so as to bring it into such relation to the barrel that the cylinder may be revolved. It will be observed that the notch D' is not at its base of greater width than the tumbler c . The use of the code finding key D illustrated in Figure 2 is the same as that described with reference to the key d in Figure 1. Having the correct notch depths for the notches D^2 , D^3 , D^4 , D^5 ma-

nipulation of the key longitudinally will enable the remaining tumbler c to be brought into proper relation by the action of the cam surface of the notch D' whereupon the cylinder may be revolved. Having thus verified the correct notch depths for four of the notches the correct depth of the remaining notch for coaction with the tumbler c may be found by trial and error in filing the key blank. 5

From the description given it will be apparent that the key maker in using the improved code finding key is concerned only with locating the key which will correctly actuate four of the tumblers and when he has located the correct code finding key his determination will be verified by 10 camming the fifth tumbler into proper relation to the barrel thereby enabling the cylinder to be revolved. Thus the number of code finding keys that must be carried in stock for locks of a particular make has been very substantially reduced 15 as pointed out hereinbefore, the difficulty of locating the proper code finding key for the particular lock to be fitted is greatly reduced and the initial investment has been correspondingly reduced. 25

It will be evident to one skilled in the art that modifications embodying the same principle may be made to meet the requirements of locks and keys of different characters but all such modifications are to be deemed within the scope of the 20 invention if they embody the principle defined by the appended claim.

What I claim is:

A code finding key for the purpose specified having a plurality of notches for coaction with the tumblers of a lock, the number of said notches being less by one than the number of said tumblers and the notches being twice as wide as said tumblers to permit longitudinal movement of the key, and a cam carried by the key and formed to engage the remaining tumbler initially when the notches of the key first release the tumblers in the inward motion of the key into the lock, the cam being further formed to move the remaining tumbler to a releasing position upon further longitudinal movement of the key equal to the width of a tumbler. 45
